FURNACE CONSTRUCTION

Application filed March 31, 1930. Serial No. 440,420.

This invention relates to furnace design and it refers more particularly to the wall structure of pipe still furnaces used in petroleum refineries.

- 5 The object of our invention is to provide a certain side wall structure that will not warp or collapse due to the intense heat and the uneven expansion which is characteristic of pipe still furnace walls.
- 10 A further object is to provide cooled, reinforcing means for furnace walls so that their strength will not be impaired at high temperatures.

This problem has heretofore been met by the use of curved front and side walls which were undesirable because of their expense, difficulty of design, difficulty of installation and their appearance. We propose to solve the problem by using a tapered outside wall 20 of common brick, the taper being from the bottom to the top on the inside, reinforced by pairs of I-beams which are mounted and cooled in the manner hereinafter described.

Referring to the drawings wherein like parts are designated by similar reference characters throughout the several views, Figure 1 is a perspective of our improved furnace with one corner broken away.

Figure 2 is a vertical section taken along the lines 2-2 of Figures 1 and 3.

Figure 3 is a horizontal section taken along the lines 3-3 of Figure 2.

The furnace may be briefly described as a rectangular structure having a front wall 10, side walls 11, and top 12. The front wall is provided with an aperture 12 and a casing 13 for admitting and mounting a gas or liquid fuel burner. The front and side walls are also provided with windows 13A through which the operator may inspect the tubes in the furnace. Corners and edges of the structure may be protected by suitable angle iron strips 14. The roof is sustained 45 from I-beams 15 in the conventional manner.

Referring more particularly to Figure 2, it will be seen that the side walls of our structure are of common brick 16 or equivalent material, and are tapered from the bottom to the top, a wall 20 feet high being about

2 feet thick at the bottom and 1½ feet thick at the top.

The entire surface of the furnace is lined with refractory material 17, the side walls of the furnace being preferably faced with a 55 uniform layer of fire brick about 9" in thickness.

To reinforce the front and side walls, we provide I-beams 18 and 19 on the outer and inner sides respectively of the brick wall and 60 clamps 20 held together by bolts 21 for holding the I-beams firmly in position. The refractory fire brick facing protects the inner I-beam as shown in Figures 2 and 3.

Since the walls of a pipe still furnace are 65 heated to high temperatures, means must be provided to cool inner beam 19. We have accomplished this cooling by providing an opening 22 adjacent the bottom of the wall by leaving a space 23 on both sides of inner 70 I-beam and by providing an opening 24 at the upper end of the I-beam.

We have found that the tapered outer wall in combination with the cooled reinforcing means above described effectively prevents 75 warping and protects the furnace walls against undue expansion forces. The space around the inner I-beam acts as a chimney and causes a circulation of air which prevents the inner beam 19 from reaching dangerously high temperatures.

While we have described a preferred embodiment of our invention it is understood that we do not limit ourselves to the details therein set forth except as defined by the 85 following claims.

We claim:

1. In furnace structure, a tapered wall, steel beams mounted in pairs on the outside and inside of said wall, clamps for holding said beams against said wall for reinforcing the same, a refractory lining protecting the inside of the wall and the inside beam, and means for circulating a cooling fluid in heat 90 exchange relation to said inner beam.

2. In furnace structure, a non-refractory wall tapered from the bottom to the top, a refractory lining on the inner side of said wall, a reinforcing beam imbedded in said 100

wall and means for circulating a cooling fluid through said beam.

3. In furnace structure, a non-refractory wall, a steel beam on the outside of said wall and another steel beam on the inside of said wall, means for securing said outside beam to said inside beam whereby said wall is reinforced, a refractory lining for protecting the inner side of the wall and the inside beam, and means for cooling said inside beam.

Signed this 24th day of March, 1930 at Wood River, county of Madison, State of Illinois.
